UNITED STATES PATENT OFFICE.

THOMAS C. BAMFIELD AND GEORGE RECHTER, OF ANGEL ISLAND, CALIFORNIA.

COMB-CLEANER.

1,177,469.

Specification of Letters Patent. Patented Mar. 28, 1916.

Application filed May 9, 1914. Serial No. 837,533.

To all whom it may concern:

Be it known that we, THOMAS C. BAMFIELD and GEORGE RECHTER, (1) a subject of the King of Great Britain and (2) a citizen of the United States, residing at Angel Island, in the county of Marin and State of California, have invented certain new and useful Improvements in Comb-Cleaners; and we do hereby declare the following to be a full, clear, and exact description of the invention, such as will enable others skilled in the art to which it appertains to make and use the same.

This invention relates to cleaners for toilet combs, and one of the principal objects of the invention is to provide a cleaner for combs comprising a bar having a series of angular projections to extend between the teeth of the comb and movable from its upper position at the base of the teeth to a point near the outer ends of the teeth for stripping or removing hairs, dandruff and other foreign matter which collects between the teeth to thus render the comb sanitary and cleanly.

Another object of the invention is to improve and simplify the construction of comb cleaners and to render them more efficient in operation and less expensive to manufacture.

These and other objects may be attained by means of the construction illustrated in the accompanying drawings, in which:—

Figure 1 is a side elevation of a comb and cleaner made in accordance with this invention, showing the cleaner in full lines, held up near the bases of the teeth, and in dotted lines showing the position for cleaning the teeth, Fig. 2 is a detail sectional view taken on the line 2—2 of Fig. 1, Fig. 3 is a detail sectional view on the line 3—3 of Fig. 1, Fig. 4 is a detail perspective view of one end of the cleaner, Fig. 5 is a detail view showing the construction of the guide member for one end of the cleaner, and, Fig. 6 is a detail sectional view showing the hinged clasp for holding the cleaner in its uppermost position when not required for use.

Referring to the drawing, the numeral 1 designates the back of a comb and 2 are the teeth, which may be all of the coarse variety, all of the fine, or part fine and part coarse. The comb 1 is provided at its opposite ends with enlarged terminal teeth 3, and near the ends of said teeth are outwardly projecting stubs 4, which serve as stops for the cleaner

bar when moved toward the end of the teeth when cleaning the comb.

The cleaner bar 5 is provided with angular projections 6, which extend between the teeth 2 of the comb for stripping the hair and other collections therefrom. At the opposite ends of the bar 5 and extending upwardly therefrom are arms 7 and projecting at right angles to said extension are the guide members or loops 8, having rectangular openings 9 therein, to receive the end teeth 3. The arms 7 are wider than the bar 5 to provide cleaning projections 6^a at the ends of the bar, as shown in Figs. 2 and 4 of the drawings. To receive the arms 7 when the cleaner bar 5 is in uppermost position, the back 1 is provided with recesses 7^a which are alined with the slots between the end and next adjacent teeth, as shown in Fig. 1 of the drawings.

Hinged centrally to the bar 5 is a clasp 10, provided with a projecting pin 11, adapted to engage an aperture in the comb back 1 to hold the cleaning bar in its uppermost position.

From the foregoing it will be apparent that by moving the clasp 10 upon its hinge and withdrawing the stud or pin 11 from the aperture in the comb back the cleaner bar 5 may be moved down toward the ends of the teeth 2 until the guide members 8 come into contact with the stop pins 4. The hair and other foreign matter may be then wiped off the cleaner bar, after which the cleaner bar 5 may be returned to its normal uppermost position, thus leaving the comb in a thoroughly sanitary condition.

The invention is simple in construction, can be manufactured at low cost, is reliable and efficient for its purpose, and is in line with progressive sanitation.

Various changes may be made in the details of construction without departing from the spirit and scope of the invention as defined in the appended claims.

What is claimed is:—

1. In combination, a comb having its back provided with recesses alined with the slots between the end and next adjacent teeth, a bar, arms extending upwardly from the ends of the bar, said arms being wider than the bar to provide cleaning projections extending inwardly from the inner side of the bar at the ends thereof, said projections being located in said slots, other cleaning projections extending from the inner side of the

bar and located in the slots between the other teeth, loops projecting outwardly and laterally from the upper ends of the arms, said recesses in the back receiving the arms 5 when the bar is in its uppermost position, releasable means for securing the bar in this position, and means for limiting the cleaning movement of the bar upon the teeth.

2. A comb cleaner comprising a bar, arms 10 extending upwardly from the ends of the bar, said arms being wider than the bar to provide cleaning projections extending inwardly from the inner side of the bar at the

ends thereof, other cleaning projections extending inwardly from the inner side of the 15 bar, and located between said first named projections, and loops projecting outwardly and laterally from the upper ends of the arms.

In testimony whereof we affix our signatures in presence of two witnesses.

THOMAS C. BAMFIELD.
GEORGE RECHTER.
